PORTABLE RECORD PLAYER OR THE LIKE

Donald F. Kaminski, Downers Grove, Ill., assignor to Warwick Electronics, Inc., Chicago, Ill., a corporation of Delaware

Filed Feb. 1, 1968, Ser. No. 10,397

Term of patent 14 years

(Cl. D56—4)

FIG. 1 is a front perspective view of a portable record player or the like embodying my new design, and illustrating the unit in a playing position with the speaker enclosures located in a unit closing position;

FIG. 2 is a top plan view thereof;

FIG. 3 is a side elevational view thereof;

FIG. 4 is a rear elevational view thereof; and

FIG. 5 is a front perspective view, similar to FIG. 1, but with the speaker enclosures moved to a location spaced generally perpendicularly with respect to the base of the unit and showing the interior, operational components.

The dominant features of the design are shown in full lines in the drawings.

I claim:

The ornamental design for a portable record player or the like, substantially as shown and described.
